UNITED STATES PATENT OFFICE.

MARY J. RUTHERFORD, OF PROVIDENCE, GEORGIA.

DESIGN FOR A CAKE-PAN.

SPECIFICATION forming part of Design No. 32,386, dated March 27, 1900.

Application filed March 1, 1900. Serial No. 7,028. Term of patent 31 years.

to all whom it may concern:

Be it known that I, MARY J. RUTHERFORD, a citizen of the United States of America, and a resident of Providence, in the county 5 of Sumter and State of Georgia, have made a new and useful Design for Cake-Pans; and I do hereby declare the following to be a full, clear, and exact description of the invention, such as will enable others skilled in the art o to which it appertains to make and use the same, reference being had to the accompanying drawings, and to letters of reference marked thereon, which form part of this specification.

Figure 1 is a plan view of a cake-pan, showing my new design. Fig. 2 is a side elevation thereof. Fig. 3 is a vertical central section.

As shown in the drawings, the material feature of my new design consists of a series o of corrugations alternately curved, as at *a*, and angular, as at *b*, the pan being made in annular shape and consisting, as best shown

in Fig. 3, of a hollow central column *c*, tapering larger downwardly, a curved bottom *d*, and sides *e*, flaring upwardly and outwardly. 25 These said corrugations, both the angular and curved ones, commence at the upper end of the hollow central column and pass downwardly and around the bottom and thence upwardly in the sides, their dividing-limits 30 being of segments whereby the said corrugations taper larger as they depart from the center.

Having thus described my invention, what I claim as new, and desire to secure by Letters 35 Patent of the United States, is—

The design for a cake-pan as herein shown and described.

In testimony whereof I hereunto affix my signature in presence of two witnesses.

MARY J. RUTHERFORD.

Witnesses:

A. P. WOOD,
EDWD. P. WOOD.
